FINGER RING HAVING TWO INTERNAL FINGER GRIPPING MEANS WITH DIVERGING ENDS

Sidney Krandall, Detroit, Mich.

Application October 29, 1953, Serial No. 389,081

1 Claim. (Cl. 63—15.6)

This invention relates to a finger ring.

Finger rings are ordinarily formed with a circular finger opening. Rings thus formed have a tendency to slip around the finger for several reasons. In the first place, the ordinary finger is not circular in cross section but generally rectangular, and when a ring is positioned on the finger, the ring does not usually embrace the entire circumference of the finger. It contacts the finger at some points and is spaced therefrom at other points around its periphery. This can be readily seen by comparing the cross section of an ordinary ring with the cross section of the finger when the ring is positioned thereon. In the second place, rings usually fit loosely on the finger because the knuckle joint between the second and third phalanges is larger in cross section than the cross section of the finger above this joint. The size of this second knuckle joint therefore in most cases determines the size of the ring.

The variation in the shape of the finger as compared with the circular opening in a finger ring and the greater dimension of the second knuckle joint as compared with the portion of the finger above this joint have been recognized before and several attempts have been made to provide finger rings which are constructed to compensate for this difference in shape and size. In some instances such as illustrated in United States Patents Nos. 1,687,020 and 1,913,463, the ring itself is fashioned with a generally rectangular shape so that when positioned on the finger, the finger opening of the ring generally conforms with the cross sectional shape of the finger. Other attempts in solving this problem have been directed along the lines of incorporating in the ring a spring member which is arranged to yieldably decrease the effective size of the finger opening so that the ring can be passed over the knuckle joint between the second and third phalanges and still snugly engage the finger when in the position in which rings are usually worn. In one form of construction, such as is shown in Patent No. 596,900, the spring member is formed from a strip of spring metal and is slidably inserted in the finger opening on the ring. In another construction such as is illustrated in Patent No. 486,720, the spring member or members are formed integrally with the ring by stamping them inwardly in the form of spring fingers from the finger-encircling band portion of the ring. A still further construction that has been proposed heretofore for the purpose of preventing a ring from turning on the finger has to do with the provision of a generally rigid insert member which is adapted to be attached to the ring after it is in the position in which it is worn, the construction being illustrated in Patent No. 1,382,043.

A more recent construction that has been suggested is shown in Patent No. 2,615,314 wherein a socket is formed in the ring and a member is telescoped within the socket and urged outwardly of the socket by springs positioned between the underside of the member and the base of the socket.

In my co-pending application Serial No. 228,853, I

2

have shown a construction for preventing a ring from turning on the finger wherein one or more rigid members are integrally connected to the finger encircling portion of the ring to diminish the size of the circular opening at the desired section.

The present invention has to do with an improved ring construction wherein yieldable means are provided for adapting the ring to the size and shape of the finger on which it is to be worn, and it is therefore an object of the present invention to provide a finger ring provided with simple spring means for accommodating fingers of various sizes and shapes which effectively prevent the ring from rotating on the finger when in place.

A further object of the invention is to provide a spring adapter for rings which can be easily and permanently mounted on a conventional finger ring for adapting a ring of a given size to various shapes and sizes of fingers.

A further object of the invention is to provide a non-turning finger ring which can be fitted to the wearer's finger very readily by the jeweler without mutilating the ring and without detracting from the ornamental appearance of the ring.

In the drawings:

Fig. 1 is a perspective view of the ring of this invention.

Fig. 2 is a side elevation of the ring.

Fig. 3 is a sectional view along the lines 3—3 in Fig. 2.

Fig. 4 shows the ring as it is worn on the finger.

Fig. 5 is a view showing the manner in which the spring member permits the ring to slip over the knuckle of the finger at approximately the lines 5—5 in Fig. 4.

Fig. 6 is a view showing the manner in which the spring member of the ring engages the fleshy portions of the finger at the location 6—6 in Fig. 4 and prevents the ring from turning on the finger.

35 In Fig. 1 there is illustrated a ring having a generally circular body portion 10 which encircles the finger and is provided with an enlarged setting 12 at the top side thereof. The setting 12 is usually larger, that is, of greater mass than the finger encircling portion 10; and under normal conditions, a conventional ring thus constructed would have a tendency to rotate on the finger because the diameter of the finger encircling portion 10 has to be sufficiently great to pass the second knuckle joint which in most fingers is larger than the cross section of the portion of the finger above this joint. The means shown in Fig. 1 for preventing the ring from rotating on the finger and at the same time enabling the ring to be passed gently over the large knuckle of the finger comprises a spring member 14. In the embodiment shown, the spring member 14 is formed as two similarly shaped pieces. The use of a pair of spring members as shown is preferred, but it will be appreciated that a single spring member rather than two can be employed if desired. The spring member 14 is fashioned as a segment of a circle and preferably extends circumferentially about 270°. Spring member 14 is permanently secured to the inner face of the finger encircling body portion 10 of the ring at the central bottom portion thereof as indicated at 16.

60 Referring now to Fig. 2 wherein the spring 14 is shown in the un tensioned condition, it will be observed that the member 14 is secured to the ring in a position disposed symmetrically with respect to the vertical central axis of the ring with the open side of the spring, that is, the side defined between the ends of the spring legs 18 and 20 disposed toward the upper end of the ring where the setting 12 is provided. In the un tensioned condition, the spring member or members 14 have a diameter substantially less than the inner diameter of the finger encircling portion 10 of the ring. Thus, with a member 14 secured to the finger encircling portion 10 of the ring at 16 as by silver soldering or the like, the

member 14 is tangent to the ring at this point; and the spring legs 18 and 20 are generally spaced from the adjacent inner faces of the portion 10 of the ring a progressively increasing distance in the direction of the free ends of the spring legs 18 and 20.

Referring now to Fig. 3, it will be noted that where two spring members 14 are employed, they are soldered or otherwise secured at the area 16 in side by side contacting relation; but these spring members preferably diverge in a direction toward their free end. This construction is especially desirable in relatively heavy rings as distinguished from thin, light rings. In a heavy ring, the body encircling portion 10 usually increases in width in a direction from the bottom side to the top side of the ring, and the spring members 14 are disposed so as to more or less conform to the increasing width of the ring. The spring members 14 are of relatively light weight and require but little tension to spread the legs 18 and 20 apart. This is desirable to provide a comfortable rather than a binding or pinching fit on the finger. However, to compensate for the relatively light grip with which the spring member 14 engages the finger, the spring member 14 is provided with serrations 24 which increase substantially the frictional engagement of the spring member 14 with the finger. The use of two spring members 14 as shown also enhances the holding ability of the light spring members.

In fitting a ring of the present invention on a person's finger, a ring size is selected such that the diameter of the finger encircling portion 10 reduced by a double thickness of the spring member 14 is sufficient to pass freely over the second knuckle joint of the finger. This is illustrated clearly in Fig. 5 which shows the extent to which the spring member 14 is expanded when passing over the knuckle joint 25 generally designated by the lines 5—5 on the finger illustrated in Fig. 4. It will be observed that when the ring is slipped over this joint, spring member 14 expands to a position wherein there is only a slight clearance 26 between the ends of the spring legs 18 and 20 and the adjacent inner surfaces of the body encircling portion 10 of the ring. The diameter of the spring member 14 in an untensioned condition is controlled by another factor; namely, the cross sectional size of the finger at a point where the ring is usually worn. This section, referenced 28, is designated by the lines 6—6 in Fig. 4, and the ring when positioned at this section of the finger is shown in Fig. 6. In the finger illustrated, the cross section at the thinner portion 28 is less than the cross section of the knuckle 25 at the line 5—5. Thus when the ring is worn in its usual position on the finger illustrated, spring member 14 is expanded to a diameter greater than its diameter in an untensioned condition (Fig. 2) but less than the diameter to which it is expanded when passing over the second knuckle joint (Fig. 5). If the cross section of the finger in the plane 6—6 were substantially smaller than illustrated in Fig. 4, then in the untensioned condition, the spring member 14 would have a diameter slightly smaller than that illustrated in Fig. 2. On the other

hand, if it should happen that the cross section of the finger at the plane 6—6 were substantially larger than the knuckle cross section at the plane 5—5, then the body encircling portion 10, as well as the spring member 14, would have a greater diameter than shown in Fig. 2.

Thus, it will be seen that by the provision of generally circular spring members such as shown at 14 and by arranging these spring members within the ring as illustrated and securing them to the ring by such simple means as silver soldering, a finger ring of a particular size can be adapted to finger which differ substantially in size and shape. Furthermore, I have found that by providing a substantially circular, relatively light spring member as illustrated and by permanently attaching the spring member to the inner face of the finger encircling portion of the ring at the bottom side thereof and in a position disposed generally symmetrically with the vertical central axis of the ring, the ring is held firmly in non-rotating condition on the finger and, at the same time, no discomfort is experienced by the wearer.

I claim:

A finger ring comprising a body portion having a generally circular finger encircling portion provided with a setting at the top side thereof, said finger encircling portion being generally of increasing width in a direction upwardly from the bottom side thereof to said setting, a pair of leaf spring members secured to the inner periphery of said finger encircling portion at the bottom side thereof, said spring members being generally U-shaped with the bight portion thereof secured to the bottom portion of the ring and each spring member being provided with a pair of arcuate spring legs extending upwardly from the bottom portion of the ring only slightly beyond the central portion of the ring, the free ends of said spring legs of each leaf spring being spaced apart a distance greater than the radius of the ring and being spaced radially inwardly from the adjacent inner face portions of the finger encircling portion of the ring, said spring legs being relatively thin as compared with the finger encircling portion of the ring and having a generally flat inner surface, said leaf springs being secured to the bottom side of said finger encircling portion of the ring in side-by-side relation and diverging in the direction of the free ends thereof, said spring legs lying entirely within the confines of said finger encircling portion whereby when said ring is placed upon the wearer's finger, said spring legs tend to maintain the ring in an upright position.
